INVENTOR

Albion D. T. Libby

UNITED STATES PATENT OFFICE.

ALBION D. T. LIBBY, OF EAST ORANGE, NEW JERSEY, ASSIGNOR TO SPLITDORE ELECTRICAL COMPANY, OF NEWARK, NEW JERSEY.

IMPULSE-COUPING.

1,390,146.

Specification of Letters Patent. Patented Sept. 6, 1921.

Application filed October 22, 1920. Serial No. 418,851.

To all whom it may concern:

Be it known that I, ALBION D. T. LIBBY, a citizen of the United States, residing at East Orange, in the county of Essex and 5 State of New Jersey, have invented certain new and useful Improvements in Impulse-Couplings, of which the following is a description, reference being had to the accompanying drawing and to the figures of 10 reference marked thereon.

This invention relates to impulse couplings. In starting internal combustion engines in which the spark for igniting the mixture within the cylinders is furnished by 15 a magneto it has been found a great difficulty has been had in securing a good spark because of the low rotative speed of the magneto. To overcome this difficulty, so called impulse couplings have been 20 interposed between the engine shaft and the magneto shaft. These devices will throw the armature shaft around with sufficient velocity to furnish a good spark within certain limits of low rotative speed of 25 the engine shaft. In devices of this character it has been found that the springs and pins against which the springs bear, which necessarily form inherent parts of the coupling, are prone to break and cause consider- 30 able trouble and expense.

It is a specific object of this invention to overcome these difficulties and to insure a more rugged and durable construction.

In the drawings which represent one em- 35 bodiment of my invention,

Figure 1 is an end view of my coupling as mounted on a magneto frame.

Fig. 2 is an interior view of my driven member with the pin of the drive member 40 shown in dotted lines.

Fig. 3 is an interior view of my drive member and

Fig. 4 is a view similar to Fig. 2, showing one end of the springs under the state 45 of compression, the other ready to take up the recoil.

Now going into detail, 1 is a plate mounted on a magneto, said magneto being provided with a shaft 2 upon which is keyed, 50 as by means of a keyway 3, my driven member 4. Said driven member is provided with two recesses 5—5 adapted to be engaged by pawl 6 pivotally mounted on said plate, as by means of a pivot pin 7. Said pawl being 55 yieldingly urged in either one of two posi-

tions by means of a link connection 8 and a spring 9. Within the driving member there is an annular recess 10 in which is mounted the stud 11, provided with two radially disposed surfaces 12, said stud being 60 apertured at 13 for the reception of an arcuate rod 14 provided with two heads 15, a bumper spring 16 being interposed between the stud and one of said heads. Also disposed within said annular recess there is 65 a compression spring 17, one end of which abuts the other head on the rod and the other end of which bears against a pin 18 mounted in the driving member 19 when the same is mounted in operative position. This pin 70 18 also has two inclined surfaces 20 similar to the surfaces on the stud 11. The drive member is provided with two slots 21 adapted to be engaged by a shaft driven by the engine. The drive member is also provided 75 with two cams 22 for a purpose to be herein-after described.

In operation the pawl 6 is thrown so as to engage one of the recesses 5. This holds the magneto shaft stationary. As the en- 80 gine shaft rotates the drive member 19 rotates therewith, the pin 18 thereof compressing the spring 17 and when the cam surface 22 engages the pawl 6 it releases the same from the recess 5, permitting the spring 17 85 to expand and throw the driven member around until the pawl 6 engages the next recess. The shape of the pawl and of the recess is such that when the engine starts and comes up to operating speed, the pawl is 90 thrown outward with such force that it is caught and held in the inoperative position.

To check the shock due to the sudden stoppage of the driven member the spring 16 together with its arcuate rod hereinbefore 95 described have been provided.

As is clearly shown in Fig. 4 the initial shock of the stoppage of the driven mem- 100 ber is absorbed by the bumper spring 16. Assisting the bumper spring is the com- pression spring hereinbefore mentioned which has one of its ends resting against one of the heads of the arcuate rod. It can be seen that even should the spring 16 be- 105 come broken that the spring 17 will still function to cushion the blow and shock of the driving member. Upon the recoil of the arcuate rod the opposite end of the spring 17 will also act as a retarding agent, and bring the parts gently to rest. 110

Having thus described my invention what I claim is:

1. An impulse coupling comprising a driving and a driven member, a post in one of said members, a rod slidable in said post, heads on said rod, a bumper spring interposed between the post and one of said heads, a pin on said other member engaging said last mentioned head, and a compression spring abutting said pin and the other of said heads. 45
2. An impulse coupling comprising a driving and a driven member, a perforated post in one of said members, a rod slidable in the perforation of said post, heads on said rod, a bumper spring interposed between the post and one of said heads, a pin on said other member engaging said last mentioned head and a compression spring 50 abutting said pin and the other of said heads. 55
3. An impulse coupling comprising a driving and a driven member, a post in one of said members, an arcuate rod slidable in said post, heads on said rod, a bumper spring interposed between the post and one of said heads, a pin on said other member engaging said last mentioned head, and a compression spring abutting said pin and the other of said heads. 60
4. An impulse coupling comprising a driving and a driven member, a post in one of said members, an arcuate rod freely slid- 65 able in said post, heads on said rod, a bumper spring interposed between the post and one of said heads, said heads and posts having opposed surfaces normal to the arc 70 of curvature of the rod, a pin in said other member engaging said last mentioned head, and a compression spring abutting said pin and the other of said heads. 75
5. An impulse coupling comprising a continuously moving driving member and an intermittently movable driven member, means 80 acting on the driven member to restrain the same against movement, means on the driving member to periodically free said driven member from said restraining influence, a post in said driven member, a rod slid- 85 able in said post, heads on said rod, a bumper spring interposed between the post and one of said heads, a pin on said driving member normally positioned to engage one of said heads, a compression spring sprung in be- 90 tween the other of said heads and said pin; said pin, during the period of restraint of the driven member, compressing the spring; said compression spring, upon release of the driven member from restraint against move- 95 ment, serving to drive the driven member and, acting in conjunction with the slid- able rod and heads, serving to cushion the shock and blow of the pin and its driving member. 100

In testimony whereof I affix my signature.

ALBION D. T. LIBBY.
